Primary Examiner — Mitchell I. Siegel*(74) Attorney, Agent, or Firm* — Schmeiser, Olsen & Watts LLP(57) **CLAIM**

The ornamental design for the lacrosse mesh, as shown and described.

DESCRIPTION

FIG. 1 is a front view of the lacrosse mesh;

FIG. 2 is another front view of the lacrosse mesh;

FIG. 3 is a close-up view of the lacrosse mesh taken along line 3 of FIG. 2;

FIG. 4 is a close-up view of the lacrosse mesh taken along line 4 of FIG. 2; and,

FIG. 5 is a close-up view of the lacrosse mesh taken along line 5 of FIG. 2.

The broken line showing of the enlarged break-out sections forms no part of the claimed design.

1 Claim, 5 Drawing Sheets(56)
